UNITED STATES PATENT OFFICE.

CECIL R. ANDERSON, OF BEN AVON, PENNSYLVANIA.

MINE-DOOR.

No. 830,281.

Specification of Letters Patent.

Patented Sept. 4, 1906.

Application filed January 17, 1906. Serial No. 296,464.

To all whom it may concern:

Be it known that I, CECIL R. ANDERSON, a citizen of the United States, residing at Ben Avon, in the county of Allegheny and State of Pennsylvania, have invented certain new and useful Improvements in Mine-Doors, of which the following is a specification, reference being had therein to the accompanying drawings.

10 Mine-doors which open and close automatically require comparatively little power for the closing movement, the greatest power being required for starting them from the full-open position. When the full power is exerted throughout the entire movement, the doors shut with a slam which is very damaging to them and to the actuating mechanism.

15 The primary object of this invention is to provide for exerting the full closing power only when starting the doors from open position, the arrangement being preferably such that the power is decreased gradually, whereby the doors are closed easily or quietly and without injury thereto or to the mechanism which actuates them.

20 With those automatically-operating doors wherein the closing mechanism is constantly active and unvarying the entire resistance thereof is encountered and must be counteracted at the beginning of the opening movement, thereby subjecting the mechanism to sudden and severe strain.

25 A further object of the invention is to provide door-actuating mechanism the resistance of which increases gradually as the door opens, thereby relieving the mechanism of strain and danger of injury incident to suddenly encountering the maximum closing power.

30 As the invention may be adapted to doors and operating mechanisms of various types the principles underlying the same may be variously embodied, one adaptation thereof being shown in the accompanying drawings, wherein—

35 Figure 1 is a top plan view of a double weight-operated door with the invention applied thereto. Fig. 2 is a side elevation of the lower portion of the operating mechanism. Fig. 3 is a front view of the doors when closed, the view being taken at line 3 3 of Fig. 1. Fig. 4 is a view, enlarged, of a portion of the mechanism, taken at line 4 4 of Fig. 1; and Fig. 5 is a similar view showing the 40 weighted arm raised.

Referring to the drawings, 2 designates the mine-track, and 3 and 3' the posts at opposite sides thereof, to which, respectively, doors 4 and 4' are hinged to swing in opposite directions. Paralleling track 2 is rock-shaft 5 50 having a series of inwardly-extending crank-arms 6, to the inner ends of which is secured the elongated depressor-bar 7, which lies close to one of the track-rails and is normally raised, as in Figs. 1 to 4. 8 is a relatively 55 short rock-shaft on the outer side of shaft 5 with its crank-arms 8' connected by links 9 to two of a series of crank-arms 10, projecting from shaft 5. Rising from shaft 8 is arm 11, connected by link 12 to door 4, which is thus 60 opened and closed by the rocking of shaft 8.

For causing the doors to swing simultaneously in opposite directions brackets 13 projecting therefrom are connected by bar 14. With the outer ends of arms 10 weighted 70 tread-bar 7 is held normally raised and the doors closed. When, however, bar 7 is depressed by the wheels of an approaching car, shaft 8 is so rocked as to open the doors, the latter being closed and the parts returned to 75 normal position by weighted arms 10 as soon as the cars pass through and off of bar 7.

Hinged to arms 10 and adapted to swing upwardly thereon are the arm extensions 15, 16, 17, and 18, provided, respectively, with 80 weights 15', 16', 17', and 18'. A stop 19 on each of arms 10 is adapted to engage the under edge of the hinged arm extension and lift the same. For stopping the downward movement of the hinged arm extensions I 85 provide uprights or rests 15'', 16'', 17'', and 18'', (here shown of gradually-increasing height,) so that as shaft 5 is oscillated by the depression of bar 7 one after the other of arms 10 raises its weighted extension, thus 90 gradually lifting the series until upon the complete depression of bar 7 and the full opening of the doors all of the weights are 95 lifted and acting counter to the door-opening force. All of the weights are thus made 100 available for starting the closing movement of the door without subjecting the mechanism to the shock or strain incident to an initial raising of them all. While all the 105 weights exert pressure for starting the door from open position as soon as the car has passed bar 7, the hinged and weighted arm extensions are rendered inactive one by one by resting on their respective supports of varying height. Thus the door is caused to 110

close under a gradually-decreasing force which prevents slamming and the jarring or racking of the ports.

The two central crank-arms 10 to which shaft 8 is connected are here shown each with a weight 10' mounted directly thereon, no pivoted weight-carrying-arm extension being used. Thus weights 10' constantly oppose the opening movement of the door and are quite sufficient to hold the same normally closed. It will be understood, however, that a greater or less number of constantly-acting weights may be provided.

As means for increasing and decreasing the power as the door opens and closes may be variously embodied it will be understood that the invention is not restricted to the construction and arrangement of weighted arms here shown. Apart from the power-varying mechanism the disclosures herein form no part of my invention. Hence various means other than a depressible bar may be used for obtaining the necessary power from an approaching car; nor is the invention restricted to a car-deflected member which moves downwardly from normal position when opening the doors.

I claim—

1. The combination of a door, car-actuated mechanism adapted to open the door, a series of resistance devices, and means whereby the devices are rendered active successively as the door opens and inactive successively as the door closes.
2. The combination of a door, car-actuated mechanism adapted to open the door, weights for resisting the movement of said mechanism, and means whereby the weights are lifted successively as the door opens and are rendered inactive successively as the door closes.
3. The combination of a door, car-actuated

mechanism adapted to open the door, weight-supports, a series of weights, and weight-lifts actuated by said mechanism and adapted to lift the weights successively from their supports as the door opens and return them successively to their supports as the door closes.

4. The combination of a door, car-actuated mechanism adapted to open the door, a series of weight-supports varying in height, a series of weights, and connections between the weights and said mechanism operating as the door opens to first lift the weight from the lowermost support and the weights successively from the higher supports.

5. The combination of a door, a car-deflected bar connected to and adapted to open the door when deflected, a series of weights, and means whereby one after the other of the weights are lifted as the bar is depressed.

6. The combination of a door, a car-deflected bar connected to and adapted to open the door when deflected, a series of arms adapted to be raised by the bar when deflected, a jointed weighted extension for each arm, and supports for sustaining said weighted arm extensions in their lowered positions.

7. The combination of a door, a car-deflected bar connected to and adapted to open the door when deflected, a shaft connected to and adapted to be rocked by said bar, a series of weighted arms on the shaft, each having an upwardly-breaking joint, and supports of different heights for sustaining the weighted outer portions of said arms.

In testimony whereof I affix my signature in presence of two witnesses.

CECIL R. ANDERSON.
